Fig. 3

appreciated that the spring 14 is adjusted or dimensioned in such a manner that the articles which strike the locking plate 12 are able to pivot this locking plate out of its locking position, into a release position as shown in full lines in FIGURE 1. In this position of the locking plate 12, the arm member 10 is able to unobstructedly pivot about the shaft member 9.

The arm member 10, when it is not in its blocked position, is pivoted back and forth between the positions illustrated in FIGURES 1 and 2 in accordance with the working cycle of the packaging machine by suitable means known to the art and here not shown. Further, the arm member 10 carries a guide plate 15 which overcomes the tendency of the incoming or advancing articles to pile up or pyramid on top of one another in superimposed or layer formation. Adjacent and downstream of guide plate 15 there is arranged a further abutment plate 15a which also prevents pyramiding of articles on top of the forwardmost article 1a adjacent the locking plate 12, particularly when the tongue members 7 are in the position shown in FIGURE 2.

Additionally, suitable transport means are provided which in the desired form shown, are constructed as a movable conveyer fork 16 which is provided with two entraining means 16a, 16b which extend into the recesses 6. This conveyer fork 16 is moved in rhythm with the operating cycle of the packaging machine via suitable means 16c. As illustrated in FIGURE 2 suitably curved guide rails are adapted to guide the conveyor fork 16 vertically during its reciprocation imparted thereto by the actuating mechanism 16c, FIGURE 3, through the path of travel 17. Thus, the conveyer fork 16 is moved by means of an appropriate drive unit 16c (FIGURE 3) from its illustrated end position of FIGURE 1 to the left of the drawing, while simultaneously undergoing a lowering movement so that its entrainment means 16a passes below the article 1a which rests against the locking plate 12 and thereafter is again raised. At the same time the arm member 10 pivots upwardly into the position shown in FIGURE 2, whereby the tongue members 7 raise one or more articles which lie directly behind the forwardmost article 1a. The entrainment means 16a of the conveyer fork 16 then displaces the article 1a towards the right into the position indicated by article 1b, whereupon the conveyer fork 16 again lowers after reaching the end of its forward stroke and is again displaced towards the left of the drawing. During the subsequent stroke of the conveyer fork 16, the article 1b is pushed onto a plunger or push rod 18 by means of the entrainment means 16b, and this article now assumes the position indicated by article 1c. During the return movement of the conveyer fork 16 the push rod 18 is momentarily raised out of the position shown in FIGURE 1, into the position shown in FIGURE 2. In this position of the push rod 18 the article 1c is grasped by suitable conveyer or transport means (not shown) and directed to a further working station of the packaging machine.

Thus, the arm member 10, the conveyer fork 16 and the push rod 18 are adapted to be driven in working rhythm with the packaging machine by the actuating mechanism 16c. The conveyer fork 16 is, however, preferably so constructed that it will move to the right when the arm member 10 is being lowered. If desired, other mechanisms can be provided for actuating the arm 10 and fork 16 by providing a suitable linkage or lever system between the arm member 10 and the conveyer fork 16. If the arm member 10 is then locked by the locking plate 12 and extension member 12a, in a manner as previously described, then the conveyer fork 16 is also in its rest position. Since the arm member 10 can only undertake a pivotal movement when an article is situated against the locking plate 12, there is thus positively insured that during each working stroke of the apparatus an article will be fed onto the push rod 18.

Having thus described the present invention what is desired to be secured by United States Letters Patent is:

1. Apparatus for separating and positioning of flat articles which are advanced in a continuous row to a packaging machine, comprising a movable support member provided with recess means and adapted to support and displace articles in a supply direction along a guideway, an arm member mounted for pivotal movement about a horizontal axis in rhythm with the operating cycle of a packaging machine, tongue means operatively connected with said arm member for movement into said recess means to raise articles from the surface of said support member, stop control means actuated by said advancing articles for permitting upward movement of the arm member, and reciprocating transport means movable beneath said tongue means during the raising of said arm member and control means and permitting the transport means to engage and further convey articles.
2. Apparatus according to claim 1, including drive means operable for imparting to said support member a reciprocatory movement, such that said support member undergoes a gentle acceleration in said supply direction of the articles and then an abrupt braking movement.
3. A device for separating and positioning articles moving in a continuous row, comprising a plate member mounted for reciprocatory movement and defining a support surface for articles, means for reciprocating said plate member, means pivotably mounted to cooperate with said plate member and the articles carried thereon which in one position thereof removes articles away from said support surface, means for oscillating said pivotally mounted means, stop means cooperating with said pivotably mounted means actuatable by said articles for permitting pivotal movement of said pivotally mounted means into said one position, and transport fork means movable beneath said pivotally mounted means during the raising of said pivotally mounted means to said one position for separating and removing the forwardmost article of said continuous row of articles.
4. A device for separating and positioning articles moving in a continuous row, comprising a plate member mounted for reciprocatory movement and defining a support surface for articles, means operatively connected with said plate member for reciprocating said plate member, said plate member being provided with recess means, arm means pivotably mounted to cooperate with said plate member and the articles carried thereon, said arm means including tongue means which in one position of said arm means moves into said recess means and removes articles away from said support surface, means for oscillating said arm means, control means cooperating with said pivotably mounted arm means actuatable by said articles for permitting pivotal movement of said pivotably mounted arm means into said one position, and transport means movable beneath said tongue means during the raising of said arm means to said one position and for separating and removing the forwardmost article of said continuous row of articles.
5. A device for separating and positioning articles moving in a continuous row, comprising a plate member mounted for reciprocatory movement and defining a support surface for articles, drive means operatively connected with said plate member for reciprocating said plate member, said plate member being provided with recess means, arm means pivotably mounted adjacent the end of said plate member to cooperate with said plate member and the articles carried thereon, said arm means being provided with tongue means which in one position of said arm means moves into said recess means and removes articles away from said support surface, control means cooperating with said pivotably mounted means actuatable by a forwardmost article of said continuous row of articles for permitting pivotal movement of said pivotably mounted arm means into said one position.

tion, said control means and said arm means being positioned such that said tongue means only raise articles situated rearwardly of said forwardmost article, and transport means movable beneath said tongue means during the raising of said arm means to said one position for separating and removing said forwardmost article of said continuous row of articles.

6. A device for separating and positioning articles moving in a continuous row according to claim 5, wherein said transport means are constructed as a substantially U-shaped conveyer fork having upright entrainment means between which an article is seized.

7. A device for separating and positioning articles moving in a continuous row according to claim 5, where-

in said control means includes a pivotable locking plate member carried by said arm means and yieldingly urged in one direction, and an abutment member positioned for contact with said locking plate member when so urged to prevent pivotable movement of said arm means.
